WALL ORNAMENT

William Earl Crawford, 5428 Spring Road,
Bladensburg, Md. 20710

Design application Aug. 24, 1964, Ser. No. 81,417, now Design Patent No. 205,515, dated Aug. 16, 1966, which is a division of application Ser. No. 70,736, June 29,
1962, now Design Patent No. 199,356, dated Oct. 13,
1964. Divided and this application Nov. 22, 1965, Ser.
No. 1,091

Term of patent 3½ years

(Cl. 29—23)

FIG. 1

FIG. 1 is a front elevation of a wall ornament showing my new design;

FIG. 2 is a top plan view; and

FIG. 3 is a side elevation thereof.

The back of the article is substantially plain and unornamented.

The essential features of the design reside in the full line portions on the drawing.

This is a division of application Ser. No. D. 81,417, filed Aug. 24, 1964, now Patent No. D. 205,515, which application was a division of application Ser. No. D. 70,736, filed June 29, 1962, now Patent No. D. 199,356.

I claim:

The ornamental design for a wall ornament, as shown and described.
